FOLDING TABLE LEG LOCK RELEASE

Sandford T. Reilly, Brooklyn, N. Y., assignor to
 Ferguson Brothers Manufacturing Company,
 Hoboken, N. J., a corporation of New Jersey

Application August 30, 1935, Serial No. 38,531

1 Claim. (Cl. 311—82)

One object of my invention is to provide a simple, effective, positively operating means for releasing the mechanism which locks upright the legs of certain types of folding tables.

5 Another object is to provide such releasing means which is located in a more convenient position than previous constructions.

A further object is to provide such releasing means which can operate with the greatest force 10 through that portion of its cycle of operation which requires it.

Other objects of my invention will appear as I describe one embodiment of it in detail. This embodiment shows my invention employed in 15 connection with such a table and table leg locking means as is shown in Willett Patent 1,950,958 (March 13, 1934), and is represented in the accompanying drawing, in which

Fig. 1 represents a detail bottom plan view of 20 a folding card table, showing my invention in locked position and (in dotted lines) in unlocked position. A portion of the side rail is shown broken away, and the legs are shown in section;

Fig. 2 represents a detail vertical section taken 25 along the line II—II of Fig. 1, looking in the direction of the arrows;

Fig. 3 represents a broken detail vertical section on a somewhat larger scale taken along the line III—III of Fig. 1, looking in the direction of 30 the arrows, the parts being shown in locked position;

Fig. 4 represents a detail view similar to a portion of that of Fig. 3, the parts being shown in unlocked position.

35 Since the detailed construction of a table similar to what I have shown is set forth in the Willett patent above referred to, I will not here describe it in detail except to say that the table top of the folding table is denoted by 1 and its boundary frame side rails by 2. Pivoted at each 40 corner is a leg 3 connected by a link 4 to a slide bar 5, each two adjacent slide bars being themselves connected by a metal tape 6 passing over pulley 7.

45 At least one of the slide bars is provided with a notch 8 on its under side. Adjacent such slide bar is mounted a resilient lock bar 9 which is rigidly secured at one end to the side rail 2. At its other end this lock bar 9 has an extending lug 10 which normally bears against the surface of the adjacent slide bar but which is so arranged that when the legs are moved to their extended positions the lug 10 will enter the notch 50 8 and will thus firmly lock the legs in position.

While the Willett patent above referred to discloses a plunger mounted through the side rail by means of which the lock bar is disengaged from the slide bar, my invention resides in the following construction, by way of example:

5 At or near the center of the table top and opposite the notch 8 there is secured a plate 11 with a screw hole 12 countersunk from its table top surface. Centered over this hole 12 is a circular block of wood 13 provided on its outer side with a handle 14 and having a segment 15 cut away on its inner surface. A center screw 16 in the hole 12 positions the block of wood while permitting it to rotate. Pivoted to the block of wood within the cut-away segment by pivot screw 17 is one end of a strap 18. The other end of this strap 18 is U-shaped and extends into a recess 19 in side rail 2 so that the main body of strap 18 runs parallel and close to the table top 1 while the U-shaped end loosely embraces slide bar 5 and the terminal portion 20 10 of the U-shaped end, when in its position farthest away from wood block 13, rests lightly against or close to lock bar 9 when said lock bar is in 15 its locked position.

In operation, a twist of the handle 14 in either direction serves to move strap 18 inwardly away from side rail 2 thus forcing terminal portion 20 20 against lock bar 9 and disengaging lug 10 on said lock bar from notch 8 in slide bar 5, so that the legs may be manually folded by operating any one. When the legs are opened, the resiliency of lock bar 9 forces it into notch 8, and pushes terminal portion 20, if necessary, to position pivot screw 17 directly in the line between center screw 30 25 35 16 and notch 8.

It should be noted that this construction delivers the greatest force at the time that both the friction between lock bar 9 and slide bar 5 and the resiliency of lock bar 9 have to be overcome, and also that the extent of the crank movement for unlocking is limited only by the distance between pivot screw 17 and center screw 16. While in the device described wood block 13 was positioned near the center of table top 1 so that its position would be fairly constant no matter what edge up the table were held, if so desired the block may be positioned elsewhere and strap 18 may be so arranged as to make somewhat less than a right angle to its cooperating slide bar. Moreover, although I have shown this invention in connection with a folding table having simultaneously folding legs interconnected, its principle may readily be applied to the unlocking of 40 45 50 55

any folding table leg which is locked by a resili-
ent action or the like.

It is evident that various other changes may be
resorted to in the construction, form, and ar-
rangement of the several parts without departing
from the spirit and scope of my invention, and
hence I do not intend to be limited to the par-
ticular embodiment herein shown and described,
but what I claim is:

5 10 15 20
10 In a folding table, a boundary frame side rail,
a foldable leg, a link for folding and unfolding
said leg, locking means parallel to said slide rail
for locking said link in unfolded position, said

locking means having a locked position and an
unlocked position, reciprocable means for mov-
ing said locking means from its locked to its un-
locked positions, one end of said reciprocable
means being U-shaped and adapted with its ter-
minal portion to contact said locking means on
its side adjacent to said side rail, and a rotatable
element provided with an integral handle, said
element being pivoted at its center to the table
top proximate the center of the table and pivoted
near its periphery to the other end of said re-
ciprocable means.

SANDFORD T. REILLY.
